UNITED STATES PATENT OFFICE.

JOSEPH W. THOMAS, OF NEW YORK, N. Y.

GREASE GUN.

Application filed May 21, 1925. Serial No. 31,733.

To all whom it may concern:

Be it known that I, JOSEPH W. THOMAS, a citizen of the United States, and resident of New York, in the county of New York and State of New York, have invented certain new and useful Improvements in Grease Guns, of which the following is a specification.

This invention relates to grease guns or other similar apparatus adapted for the delivery of lubricant or other semi-liquid or plastic material under pressure to the point of use. It relates more particularly to that type in which the container for the shipment or storage of the material, is employed in whole or in part, in connection with the grease gun parts during the delivery of the contents of said container.

In my improved construction the grease gun per se includes a cylinder of such diameter that it may be forced into the barrel or body portion of a cylindrical container or can and substantially snugly fit the interior thereof. As one improved feature, I make this cylinder longer than the container so that when the caps or closures for the ends of the barrel or body of the container are removed, the cylinder may be forced through the container body and project from both ends thereof. The cylinder has an end wall which carries a plunger screw or piston rod while the other end wall is removable and has the delivery outlet. Both of these end walls are directly connected to the cylinder so that the barrel or body of the container may form a jacket for the cylinder of the grease gun and will be held in place against both longitudinal and rotary movement in respect to the cylinder during the dispensing of the material. The label or name on the container will indicate the material with which the grease gun is loaded, and, as a new jacket of this kind is placed on the grease gun cylinder for each charge of the latter, the exterior of the grease gun, may be kept clean and free from grease and with less likelihood of soiling the hands.

In the accompanying drawings,

Figure 1 is a perspective view of a container adapted for use with my improved grease gun,

Figure 2 is a perspective view showing the position of the parts during the loading or charging of the grease gun,

Figure 3 is a central longitudinal section of the grease gun,

Figure 4 is an end view of the grease gun with the outlet cap removed, and

Figure 5 is a side elevation, partly in section, of a modified form of connection between the end wall and piston rod,

My improved grease gun is adapted for use in connection with a container or can shown particularly in Figure 1, and which includes a barrel or body portion 10 and a pair of removable end walls or caps 12 and 13. The body portion has a bead which may form a stop for the edge of the flange of the top cap 12, said bead being preferably formed of separate sections 14. The container may be made of sheet metal or of any other desired material such, for instance, as cardboard or the like, depending upon the nature of the material to be shipped and stored therein.

The grease gun includes a cylinder 15 of an exterior diameter but slightly less than that of the interior diameter of the container body 10, of a length somewhat greater than said body so that the cylinder may be forced into the container, upon the removal of the caps from the latter, and will project from both ends of said body.

The cylinder has a top end wall 16 which may be in the form of a cap threaded, welded or otherwise secured thereto or in some instances, it may be made integral therewith. This top wall 16 has a center opening through which extends the piston rod 17 of a piston 18. The piston rod is preferably threaded and engages with a collar 19 which is detachably secured to the end wall 16. It may have threaded engagement with a boss 20 as shown in Figures 2 and 3, or it may have a bayonet slot 21 for engagement with a pin 22 on a similar boss 20^a as shown in Figure 5. By detaching the collar 19 from the end wall the piston rod may freely slide through the end wall but when the collar is attached, said piston rod can be moved endwise only upon rotating it to screw it through the collar.

The cylinder at its opposite end, is provided with a removable end wall or cap 23 which has the dispensing outlet 24. This outlet may deliver to a nozzle, a flexible hose or any other suitable means for conveying the grease or other contents to the point of use. One of the end walls as for instance, the wall 16, is provided with means for engaging with the body of the container to prevent relative rotation of the latter on the

- cylinder when said body is in place as a jacket on the cylinder. As shown, the cap 16 has a depending flange 25 beneath which the upper end of the jacket may extend and this flange has recesses 26 for receiving the beads 14 on the jacket or container body 10. The lower cap or end wall 23 has a flange 27 which may project over and conceal the lower end of the jacket or body wall 10.
- 10 In charging the grease gun, the top cap 12 is removed from the container and the end of the cylinder is forced into the container. By holding the container in one end and by pressing down and rotating the handle 28 of 15 the piston rod, the piston will be screwed up into the cylinder and at the same time the cylinder will be forced down into the container. When the cylinder reaches the bottom of the container and all of the grease 20 has been forced into the cylinder, the lower cap 13 on the container may be removed and the body portion thereof forced to effect interlocking engagement of the bead sections 14 and the recesses 26. The lower end wall 25 of the grease gun may then be screwed directly onto the lower end of the cylinder to hold the container body in place on the cylinder. Thus the container body may remain on the cylinder during the use of the 30 contents of the container so as to form a jacket for the grease gun which will indicate the contents of the grease gun and will present a clean and fresh surface each time the grease gun is reloaded. If the material to 35 be dispensed by the device is of very low viscosity, it may be ejected by unscrewing the collar 19 and forcing the plunger down by direct endwise movement of the piston rod. If the material is of a more viscous 40 nature or requiring more force to eject it, or to force it to the point of use, the collar may be secured in place and the piston rod rotated to move the piston or plunger downwardly at a slower and more easily controlled rate.
- Having thus described my invention what I claim as new, and desire to secure by Letters Patent is:—
1. A device for dispensing the contents of 50 a cylindrical container having removable end walls, said device including a cylinder adapted to be projected axially through the body of the container and to closely fit the latter with both ends of said cylinder projecting 55 beyond the ends of said body, and a pair of end walls, one having a dispensing outlet, a piston having a piston rod projecting through the other end wall, one of said end walls being removable and said end walls 60 having means for engaging the end portions of the container upon the outside of said cyl-

inder and prevent relative rotation of the cylinder and container.

2. A grease gun including a cylinder, a pair of end walls each having a flange encircling said cylinder with the edge portion spaced therefrom, one of said end walls being removable whereby a jacket may be slipped onto said cylinder, and held between and beneath said flanges, a piston having a rod projecting through one of said end walls, the other of said end walls having a dispensing outlet.

3. In combination, a container for plastic material including a cylindrical body portion and a pair of removable end caps, said body portion having a bead adjacent to one end and formed of spaced sections, a cylinder adapted to be projected through the body of said container and projected beyond the ends thereof, means engaging said beads for preventing relative rotation of the container and said cylinder, end walls for said cylinder, one of said end walls having detachable connection with the cylinder, and means for forcing material from said cylinder.

4. A dispensing device including a cylinder having a pair of end walls, one of said walls being removable, a piston within said cylinder having a piston rod extending through one of said end walls, the other of said end walls having a dispensing outlet, and a container having a cylindrical body portion adapted to be slipped end-wise onto said cylinder upon the transfer of the material from said container to said cylinder, and said body portion being adapted to serve as a jacket on said cylinder during the dispensing of material from the latter, said end walls engaging with said jacket to prevent relative axial or rotational movement of the jacket and cylinder.

5. A grease gun including a cylinder having a pair of end walls, each having an aperture therethrough, one of said apertures serving as a dispensing outlet and the other to receive a piston rod, a piston within said cylinder having a threaded piston rod, a cap detachably secured to said second mentioned end wall and having threaded engagement with said piston rod, said first mentioned end wall being detachable from said cylinder and having threaded engagement therewith and said end walls having means for engaging with the ends of the body portion of a container upon the slipping of the latter onto said cylinder, and the transfer of the contents of the container to the cylinder.

Signed at New York city in the county of New York and State of New York this 19th day of May A. D. 1925.

JOSEPH W. THOMAS.
